UNITED STATES PATENT OFFICE.

CHARLES F. BLACK, OF SAN FRANCISCO, CALIFORNIA, ASSIGNOR TO THE PRESTO-COPY COMPANY, A FIRM COMPOSED OF CHARLES F. BLACK, M. L. BLACK, AND TWONNETTE PARKER, OF SAN FRANCISCO, CALIFORNIA, AND LOWELL PARKER, OF LOS ANGELES, CALIFORNIA.

STENCIL DUPLICATOR.

Application filed December 23, 1925. Serial No. 77,237.

The essential elements for a duplicator of this type are:

First, an even and absolutely level printing surface which will remain true and even after prolonged use and in all conditions of atmosphere and temperature.

Second, a thoroly balanced construction so that an even and uniform pressure on the handle will produce an even and regular 10 rolling or rocking movement of the stencil surface on the surface to be printed, thus eliminating all necessity for guiding or directing by the hand.

Third, a method or provision for placement which will operate automatically and with greater accuracy, speed and uniformity than can be accomplished by the eye.

Fourth, a simple, convenient and durable 20 device by which to fasten or clamp the stencil on the pad so as to prevent wrinkling or slipping, and yet so delicate and soft as not to tear or fracture the stencil paper.

I have provided for each of the foregoing requirements as follows:

The first, i. e., an even level and durable 25 surface. Makers of this type of machine have tried metals of various kinds, but have found that they all warped or buckled under varying degrees of temperature; hard rubber, but it will give and reshape with heat or under continued pressure; wood, either sawed from solid blocks or veneered, both forms have failed on account of warpage. The net result has been devices of varying 30 degrees of efficiency to start with but all becoming crooked or warped after a little usage and so useless. I have overcome this difficulty by the method hereinafter described of selecting, curing and finishing.

The second requirement is accomplished 35 by the laminated construction above described. As the length of the grain runs across the face and as the different woods are laid in at regular intervals and as all exposed surface is the flat of the grain, then the final accurate sawing is done after all parts are assembled and time is allowed for warpage and adjustment, I secure a perfectly true and accurate face of uniform quality, texture and weight.

I have found the arc of curvature and the position and relation of the handle to that

arc to be essential elements. I have found that arcs of a radius approximately 6" are best adapted to small machines having a 45 lengthwise printing surface of not more than 6" and the size of the arc should be gradually increased proportionately with the length of the printing surface to 8" for a 50 printing surface of 12". And in all sizes 60 the top of the handle to be grasped by the hand, and where the pressure should be applied, must be the approximate radius of the 65 arc and must be located in the approximate center of said arc. This careful relation of 70 arc and handle length and position makes it possible to rock the stencil over the paper with practically all the pressure exerted vertically, thus eliminating all pushing or sliding tendency which always results in 75 wrinkled stencils and blurred printing.

Third, placement has always been a great difficulty with this type of duplicators. I have provided for this by extending the body 80 of the machine beyond the clamp grooves (see #4 and #9 in figure), so as to form a straight edge and level face, #14 and #15. exactly true with the printing face of the machine. By placing a moderate sized stack of paper in position, placing the fingers of the left hand lightly at the top, then placing the level surface #15 firmly against the bottom of the pile, the printing surface is 85 automatically and exactly trued to the surface to be printed. Then as the rocking begins, the shoulder beyond the clamp grooves 90 catches the top of the pile and the placement is perfect. By providing this arrangement on both ends of the machine and by allowing room for a slight adjustment up and down 95 of the stencil on the pad, I provide a most perfect and wonderfully adaptable method of placement. This placement extension is also used as a rest for the machine, thus saving wear on the stencil and ink spots 100 on the furniture.

Fourth, clamping the stencil. This is provided by a U-shaped spring steel wire of sufficient weight to provide adequate strength. The middle or center length of the wire is slightly in excess of the width of the machine and is curved inward at the center so as to give an even pressure the entire width of the stencil paper. This

section is also covered with rubber tubing to prevent unnecessary tearing of the stencil. The sides or end sections of the U extend along the sides of the machine and are 5 curved upward toward the printing face. Toward the ends of these wires and leaving about $1\frac{1}{2}$ " for play is provided a hinged or swinging clip fastened to the side of the machine. Through the face of this clip a 10 hole is provided slightly larger in diameter than the diameter of the wire used. The wire end passes through this hole and a sharp bend at the extreme end prevents its coming out. When the stencil is in place 15 on the pad its ends extend well into the grooves. Then the operator passes the transverse section of the wire over the end of the stencil extending into the groove and by a firm pressure with the thumbs along 20 the curved portion of the sides forces the ends to expand slightly through the side clips. At the same time with the fore fingers he pulls backward on the clips until 25 they firmly contact the wire. Then releasing the thumb pressure the recoil of the spring fixes the grip of the clip and leaves the ends of the stencil under a firm even pressure. Both the clip and the wire are made 30 of very hard steel so there is no possibility of serious wear.

As above pointed out, the first and prime necessity in the construction of a pad duplicator of the above stated type is the provision of an even and absolutely level printing surface which will remain true and even after prolonged use and in all conditions of weather and temperature. Duplicators heretofore constructed have been thus true when new but after being used for making 35 a few hundred copies have become so uneven as to make a very irregular and entirely unsatisfactory copy. The stenciling portion of these duplicators has been made of various materials. Metal is not suitable 40 on account of its tendency to warp or buckle in changing temperature. Hard rubber is impractical because of its pliability under continued or repeated pressure. Wood is apparently the only practical possibility 45 and because of its tendency to warp, swell, and shrink under various atmospheric conditions, this has not heretofore been at all satisfactory. It is an object of my invention to provide an improved stencil duplicator of wood and to manufacture the same by a process which entirely overcomes the 50 objections heretofore known, and to produce a duplicator which will keep its original uniform printing surface under all conditions.

In the accompanying drawing and specification I have illustrated and described one specific embodiment of my invention, but it will be understood that the invention can 55 be otherwise embodied and that the draw-

ing and specification are not to be construed as defining or limiting the scope of the invention, the claims appended to the specification being relied upon for this purpose.

Referring to the figures of the drawing, Fig. 1 is a perspective view of a stencil duplicator constructed in accordance with my invention.

Figure 2 is a side elevation thereof partly in section.

In the drawing, 1 indicates the body portion of my stencil duplicator having a convex arcuate stenciling face 2 on one side and a handle 3 projecting from the opposite side. As above stated, the stenciling face 2 must be entirely level transversely and entirely uniform throughout if the printing performed thereby is to be even and clear. In duplicators heretofore manufactured, this face has become uneven and the duplicator therefore unsatisfactory and useless. As illustrated in Fig. 2, I provide the body portion 1 of laminated wood so treated and assembled that the face 2 remains even and uniform at all times and under all conditions.

For the duplicating portion of the device, I select entirely clear straight grained boards of two different grains, one being a rather open well defined grain such as sugar pine, and the other a finer more even grain such as is found in Mexican birch. I select about equal amounts of heart or center cuts only, no sap or surface boards being used. These boards are from 8 to 12 inches wide and three-fourths of an inch thick, and very carefully surfaced on both sides.

For the ends 4 of the duplicator I use pieces of hardwood such as eastern birch. These pieces should be 2 inches thick and the width of the other boards. For the handle 3 and its center strut portion 3' I use a good quality of straight grained oak one and one-half inches thick and of sufficient width to cut the strut complete without piecing. For the sides of the duplicator any good straight grained heart lumber one inch thick, is used.

After assuring that the lumber selected is absolutely dry and seasoned, I pile the boards intended for the body portion of the duplicator in quick hardening cold glue under heavy pressure in what is known as a laminated construction, first a piece of eastern birch, then several alternate pieces of Mexican birch and pine, and thereafter another piece of eastern birch. After this pile has remained in the press until the glue is entirely set and all tendency to warp and spring has passed, ordinarily about twenty-four hours, it is sawed into lengths exactly as long as the face of the duplicator for which it is intended to be wide. These blocks are then taken to a band saw with the blade thereof running lengthwise of the

5 grain of the wood and a "shape" is sawed out having the exact curve desired for the duplicator face. This sawed out "shape" comprises two hardwood end pieces and the intermediate pieces of the pine and Mexican birch, and is seven-eighths inches thick whereby to permit a second sawing thereof hereinafter described.

10 The sides 5 and handle member 3 are sawed and shaped by ordinary processes. The duplicator is then assembled by hand, thoroughly nailed, glued, and given time to set into definite shape. It is then again operated on by the band saw. The assembled duplicator is clamped into a swivel, the distance from the fulcrum or swinging point of the swivel to the blade of the saw being carefully adjusted to the radius of the circle subtended by the arc of the duplicator face 2. The extra thickness allowed in the first sawing is then taken off in as near a perfect shape as possible, leaving a surface 2 theoretically true and perfect.

15 The device is then nicely smoothed in a finishing operation and immediately, without allowing any time for dampness to get into the wood, immersed into a vat of linseed oil at about 65 to 70° temperature and allowed to remain from fifteen to thirty 20 minutes or until all the joints and interstices of the joining have been thoroughly filled and the fiber of the wood has been well saturated. The surplus oil is then drained off and the duplicator is laid away in a well 25 ventilated, slightly warm room until it is completely dried through.

30 This drying process requires from four to six weeks depending upon the nature of the wood, some wood absorbing much more oil than others. At the end of this time the device is thoroughly seasoned and the fiber of the wood filled by a tough unyielding gum. This in conjunction with the nature 35 of the woods used, tends to so balance the face 2 as regards heat and cold variation, that a device is provided which will remain constant under all conditions.

40 To be doubly assured that the device will remain constant, I give the same as above completed two liberal coats of pliable filler and surfacer, insoluble in water, gasoline, or turpentine. This filler is similar to that used on aeroplane wings. This coating is then given ample time to dry and to allow 45 any possible spring or warping of the duplicator.

50 These various coatings always result in slight changes in the face 2 of the device, caused by such action as one piece of wood absorbing more oil than the adjacent piece. Therefore, after all these processes are completed and time allowed for any possible changes, usually from six to eight weeks in process, I give the face 2 a final trueing. 55 I attach a sheet of coarse sand or grit paper

to a perfectly true and level surface and sand the face 2 until there is not a streak or spot of light shown under a straight edge held transversely across such face.

5 The pad 6 which is to be saturated with 70 ink, consists first of a piece of press-board or gasket board impervious to ink or moisture, so as to protect the face 2 from any possible chemical action. On this is placed a heavy piece of closely woven and very 75 smooth woolen fabric and over this a thin finely woven cotton cloth for appearance and to strain any lumps of impurities from the ink and so protect the life of the pad. This pad is made up complete and then 80 attached to the face of the block with glue under strong even pressure.

As illustrated in Fig. 2, the body portion 2 of the device contains alternate pieces or laminations of sugar pine 7 and Mexican 85 birch 8, and the end pieces 4 of eastern birch. The body 2, sides 5, and handle 3 are assembled in the manner illustrated and described. The ends 4 are grooved at 9 in a manner receiving the mid portion 10 of a U-shaped clamping member therein, the ends 11 of the member extending along the sides 5 of the duplicator. Clamping latches are pivoted to the sides 5 and have holes therethrough receiving the wire ends 11. 95 The arrangement is such that the portions 10 can engage the ends of a stenciling strip and hold the same tightly onto the pad. By pressing downwardly on the wires 11 in the direction shown by the arrows in Fig. 1, such wires can be forced through the latches 12 in a manner tightening the members 10 in the grooves 9. The canting action 100 of the latches against the wires 11 holds the wires tightly secured. The same can be readily released by forcing the latches backwardly on the pivots.

105 The operation of the device is illustrated in Fig. 2. A stack of blank sheets to be stenciled is shown at 13. The operator grasps the handle 3 and places the end 4 against the stack 13 and then rolls the padded face 2 over the top sheet. The printed top sheet is then removed and the operation 110 repeated. As will be noted, the end 15 in combination with the face 13 serves as a placement to automatically locate and place the printing face 2 in the proper position on the sheet, the operator being required to only place the end 15 against the stack and roll duplicator. This end construction for 115 this placement purpose is one of the novel features of my invention.

120 Another very novel feature of my invention resides in the handle 3. It will be understood that to secure a clear clean cut print, the duplicator face 2 must have an entire rolling action with the paper 13. In 125 duplicators as heretofore constructed, certain portions of the copy have been rough 130

and blurred for the reason that the printing pressure on the duplicator handle has tended to slide the duplicator over the paper being printed. It will be noted that the curved surface 14 of the handle 3 which is engaged by the palm of the operator's hand is located at the center of the arc defined by the face 2. This being true, the entire pressure exerted on the handle portion 14 to roll the face 2, will always operate to roll the duplicator on such face across the entire sheet 13. With the handle thus located, the duplicator will never tend to operate with a sliding action and therefore the copy made will be clear and clean cut.

It is believed that the construction, operation, and advantages of my invention will be clear without further description herein.

Having thus described my invention, what I claim is:

1. A stencil duplicator comprising a body portion having a convex arcuate bearing face and a centrally disposed handle for the duplicator having the hand engaging portion thereof located at the geometrical center of the bearing face, whereby in operation manual pressure on the handle is transmitted into a rolling action of the duplicator at the said bearing face.

2. A stencil duplicator comprising a body portion having a convex arcuate bearing face and a bearing support adjacent one end of the said face and separated therefrom by a rearwardly spaced surface, the support providing a rest for the duplicator in operation and the said surface providing a placement means between the rest and bearing face.

3. A stencil duplicator comprising a body portion having a convex arcuate bearing face having a retracted placement surface thereacross adjacent each end thereof, each end of the face serving as a rest for the duplicator in operation and the said surface providing a placement means between the rest and the operating portion of the bearing face at the other side of the surface.

4. A stencil duplicator comprising a body portion having a convex arcuate bearing face having a placement groove provided therein across and adjacent each end thereof, and a pair of stencil clamping members connected to the duplicator and extending along the grooves, the ends of the body be-

yond the grooves each providing a placement edge for the duplicator in operation.

5. A stencil duplicator comprising a body portion having a convex arcuate bearing face having a placement groove provided therein across and adjacent each end thereof, a pair of stencil clamping members each comprising a stencil engaging portion extending along its groove and two legs extending along the side of the duplicator, and a locking member for each leg pivoted to the duplicator and adjustably receiving the leg therethrough, the legs being freely slideable in the tightening direction in the locking members and automatically held against movement in the opposite direction by the canting action of the members thereon.

6. The method of making a laminated stencil duplicator, consisting of providing a laminated block made up of layers of alternately different, well-seasoned wood held together by glue, sawing therefrom the body portion of a stencil duplicator of the shape having an arcuate stenciling face of that desired in the finished duplicator, providing cooperating blocks, forming such blocks and the said body portion into a duplicator unit, thereafter immersing the unit in linseed oil until the same is saturated, and thereafter thoroughly drying the unit and oil therein.

7. The method of making a laminated stencil duplicator, consisting of providing a laminated block made up of layers of alternately different well-seasoned wood held together by glue, the end layers being of hardwood and the intermediate layers of two alternately different soft woods of different grains, sawing therefrom the body portion of a stencil duplicator of the shape having an arcuate stenciling face of that desired in the finished duplicator, providing cooperating blocks, forming such blocks and the said body portion into a duplicator unit, immersing the unit in boiled linseed oil until the same is saturated, thoroughly drying the unit and oil therein, and thereafter treating the unit with a coating of waterproof filler, the hardwood ends being adapted to form the supporting ends of the duplicator and the intermediate soft wood being adapted to form the stencil portion of the duplicator.

CHARLES F. BLACK.
